PRODUCTION OF DISTILLATE

William M. Stratford, New York, N. Y., assignor,
by mesne assignments, to The Texas Company,
New York, N. Y., a corporation of Delaware

Application May 8, 1941, Serial No. 392,538

7 Claims. (Cl. 183—114.6)

This invention relates to a process for the production of distillate reservoirs wherein liquefiable hydrocarbons are recovered from the fluid flowed from a well tapping a reservoir of this type, and residual gases are preferably returned to the same or a different distillate reservoir for the purpose of maintaining formation pressures.

It is the principal object of the invention to provide a novel and efficient process for the recovery of liquefiable hydrocarbons from distillate fluids which possesses important advantages over the processes heretofore proposed for this purpose.

Other objects of the invention will in part be obvious and in part will appear hereinafter.

In the production of hydrocarbons from a distillate reservoir, it is recognized that in order to prevent the condensation of liquefiable hydrocarbons in the reservoir itself, which results in permanent loss of hydrocarbons, the residual gases should be returned to the reservoir so as to avoid as far as possible any drop in pressure in the formation. The fluid flowed from a well tapping a distillate reservoir is under such conditions of temperature and pressure that the fluid exists substantially as a homogeneous gas phase. The temperatures of typical distillate fluids at the well head are of the order of 125 to 175° F. and the pressures are of the order of 1500 to 5000 pounds per square inch or above. A reduction in the pressure of this fluid causes condensation of hydrocarbons. Accordingly, most of the processes which have been employed for the recovery of hydrocarbons from distillate fluids have involved as an essential feature materially reducing the initial pressure of the fluid. Because of the necessity of returning the residual gases to the formation under pressures exceeding the formation pressures, the reduction in pressure above ground has added materially to the costs of the processes.

Absorption processes using a relatively heavy absorption oil have also been employed. These processes have involved a single stage oil absorption carried out at a pressure below 2,000 pounds per square inch in which, after cooling the distillate fluid from its initial temperature to a lower temperature considered desirable for absorption, the fluid is passed into contact with a cool absorption oil to absorb liquefiable hydrocarbons and yield residual gases which are compressed and returned to the formation.

In considering the conditions under which processes for the recovery of liquefiable (i. e. normally liquid) hydrocarbons from distillate fluids

are carried out, it is of advantage to keep in mind the phase relations of the fluids. For a discussion of phase relations see the article, "Retrograde condensation," by D. L. Katz and F. 5 Kurata, Industrial and Engineering Chemistry, vol. 32, No. 6, June 1940, pages 817-827. In the reservoir a distillate fluid is considered to exist as a single phase and the conditions at which the fluid is flowed from a well are usually somewhat within the two phase boundary on the 10 temperature-pressure plane. Thus the temperatures in the reservoir and at which the fluid is flowed from the well are above the temperature at the critical point for the fluid, and the pressures on the fluid in the reservoir and when the 15 fluid is flowed from the well are usually not substantially below the pressure of the two-phase boundary at the existing temperature. It will be understood that where the conditions of temperature and pressure of a distillate fluid are 20 near the two-phase boundary in the critical area, raising the temperature and/or pressure serves to move the conditions away from the two-phase region; i. e., away from conditions at which condensation of liquid takes place.

In accordance with the present invention the fluid flowed from a well tapping a distillate reservoir is intimately contacted with a medium consisting essentially of water to remove liquefiable 25 hydrocarbons from the fluid and leave residual gases which are preferably returned at least in part to a distillate reservoir for the purpose of maintaining formation pressures. The contact between the fluid and the medium may be and 30 preferably is accomplished at a pressure not substantially below well head pressure. Also the temperature during the contact may be maintained substantially at the temperature at which the fluid is flowed from the well, somewhat below this temperature, although preferably not 35 sufficiently low to permit the formation of hydrates, or at an elevated temperature. The temperature at which the operation is carried out has an effect on the solvent action of the water.

40 The advantages of proceeding as described above are more or less apparent. As compared with absorption processes, the process has the advantage that inexpensive water rather than an absorption oil is used, and also, whereas absorption 45 processes are preferably carried out at a temperature substantially below the temperature at which the fluid is flowed from the well, the process does not require cooling. As compared with the so-called retrograde condensation processes, in which cooling and a reduction in pres-

sure are relied upon for causing condensation, the process has the advantage that cooling is not required and it may be carried out at substantially well head pressures or higher pressures. The residual gases, therefore, are obtained in any case at a pressure only slightly below well head pressures. This is, of course, a distinct advantage where the residual gases are to be returned to a distillate reservoir, which is the usual situation.

As pointed out above, the temperature of the fluid flowed from a distillate well may vary from in the neighborhood of 125 to 175° F., and the present process may be carried out at temperatures of this order. The process may also be carried out, however, at elevated temperatures; for example, at temperatures above 200° F. and especially at a temperature within a range of 400 to 600° F. The distillate fluid and the aqueous medium will ordinarily be at substantially the same temperature at the time of bringing them into contact, but in certain cases the temperature of the fluid may be somewhat below the temperature of the medium.

In addition to water the essentially aqueous solvent employed in the present process may contain additives which upon admixture with water produce a solution adapted to dissolve or absorb hydrocarbons containing four or more carbon atoms at elevated temperatures and pressures. These additives also preferably are such as to produce a solvent mixture in which hydrocarbons containing four or more carbon atoms are relatively insoluble at low temperatures. As additives for this purpose there may be mentioned hydroxy and polyhydroxy organic compounds which are substantially completely soluble in water at least at elevated temperatures. Representative examples of compounds of this class are dihydroxy saturated and unsaturated alcohols such as ethylene glycol, polyethylene glycols, trimethylene glycol, butylene glycol, and polyolefin glycols; halogenated derivatives of the dihydroxy alcohols such as trimethylenechlorhydrin, glycerol alpha and beta dichlorhydrins, and ethylene chlorhydrin; alkyl ethers of the glycols such as ethylene glycol mono methyl ether and ethylene glycol diethyl ether; alcohols such as ethyl alcohol, poly-vinyl alcohol, and allyl alcohol; poly-hydroxy alcohols such as glycerine, mannitol, and sorbitol; phenolic compounds such as phenol, resorcinol, phloroglucinol, pyrogallol, and substituted derivatives thereof; hydroxy acids such as salicylic and lactic acids, and salts thereof; and amino and nitro derivatives of alcohols such as monoethanolamine, diethanolamine, triethanolamine, and 2-nitro ethanol. The proportion of the additive may range from a fraction of 1 per cent to 50 per cent or more by weight of the solvent mixture and preferably will range from 5 to 25 per cent by weight.

The aqueous solvent may also consist of water to which has been added an agent adapted to reduce the surface tension of the water, or a solvent mixture of the type discussed above containing in addition an agent for reducing the surface tension. Agents for reducing surface tension of water are well known and comprise, for example, compounds such as water-soluble soaps (e. g. alkali metal oleates), and synthetic wetting agents and detergents, examples of which are alkyl aryl sulphonates, alkyl sulphates, and esters and amides of higher fatty acids with lower sulphonated alcohols and amines. In gen-

eral the synthetic detergents are characterized by containing a straight or branched alkyl chain of at least 8 and preferably 12 to 16 carbon atoms and a solubilizing group such as a sulphate or sulphonate group and are usually employed in the form of the alkali metal, including ammonium, preferably sodium, salts. Detergents of this type are represented by the products marketed under the trade names, Nacconol, Gardinol, and Igepon.

10 In order that the invention may be understood more fully reference will be made to the accompanying drawing in which is illustrated one manner of operating the present process.

Referring to the drawing, a distillate fluid is 15 flowed from output well A, which taps a distillate reservoir, through valved line 10 leading to a heat exchanger 11. In this heat exchanger the fluid is brought into indirect heat exchange relationship with the relatively hot fluid flowing in line 32, as will presently be described. From the heat exchanger the fluid flows through a heater 12. As noted above, distillate fluids are normally removed from the well at a temperature in the neighborhood of 125 to 175° F. and at an elevated 20 pressure, the conditions of temperature and pressure together being usually not substantially within the two-phase boundary for the fluids on the temperature-pressure plane. In accordance with this embodiment of the invention the fluid 25 is heated in the heat exchanger and heater to a temperature above 200° F., for example, a temperature within the range of about 400 to 600° F. From the heater, the fluid passes through line 14 leading to a mixing tower 16. Water is introduced into the fluid flowing in line 14 through line 18, the water being at about the same temperature as the fluid. The amount of water used may vary, but ordinarily will be used in considerable excess. For example, the aqueous medium 30 may be used in proportions corresponding to a liquid volume ratio of medium to hydrocarbons which it is desired to absorb of 20:1 to 200:1 or more.

40 After the introduction of water, the mixture of 45 the distillate fluid and water flows into the lower portion of mixing tower 16. This tower is preferably provided with means, such as Raschig rings 20, for inducing intimate contact of liquid and gases. The mixture then flows from the upper portion of mixing tower 16 through line 22 to a separator 24. In the separator, which is preferably provided with baffles at least in the upper portion thereof, a separation is accomplished between residual, undissolved gases, largely gases composed of hydrocarbons having three or less carbon atoms, principally methane, and an aqueous phase consisting of the water and dissolved or absorbed hydrocarbons. The residual gases are removed from the top of tower 24 50 through line 26 leading to a compressor 28. The compressor serves to raise the pressure on the residual gases to a sufficiently high point to return them to the distillate reservoir tapped by well A, through valved line 30 and input well B. 55

The hot aqueous fluid is removed from separator 24 through line 32 leading to heat exchanger 11 where the aqueous fluid gives up part of its heat to the incoming well fluid. From the heat exchanger, the aqueous fluid passes into line 33 60 leading to a cooler 34. In this cooler the temperature is reduced to a sufficiently low point to affect adversely the solubility of the heavier hydrocarbons in an aqueous medium; for example, to a temperature not above 100° F. At this low 65 temperature, the liquid flows through line 36 to

the middle portion of a settler 38 wherein the liquid is permitted to settle and separate into an aqueous and a hydrocarbon phase. The hydrocarbon phase is removed from the upper portion of the settler through valved line 40 leading to a flash tank 42 wherein the pressure on the hydrocarbon mixture is reduced to about 500 pounds per square inch. Gases formed due to this reduction in pressure are removed from the top of the tank through valved line 44. These gases, by means not shown, are preferably used for heating the fluid passing through heater 12. Any water settling out of the hydrocarbon mixture in this tank may be removed through valved line 46. From tank 42 the hydrocarbons are passed through valved line 48 leading to a second flash tank 50 in which the pressure is maintained at about 30 pounds per square inch. The gases are removed from this tank through valved line 52 and may be used for heating the incoming fluid or for heating the water used in the process. The final hydrocarbon mixture or condensate is removed to storage through valved line 54.

The aqueous phase formed in settler 38 is continuously removed from the bottom thereof through line 56 which is provided with a pump 58. The aqueous medium is then passed through the heater 60 which is operated to raise the temperature of the medium to about the temperature of the fluid flowing in line 14 and the heated medium then passes into line 18 for reuse in the treatment of the distillate fluid. Water make-up may be introduced into the system through valved line 62.

It will be understood that the above described manner of operating may be varied. For example, the process may be operated by maintaining a body of water and passing the fluid therethrough. In this case, an aqueous mixture of water and dissolved or absorbed hydrocarbons is continuously removed from the contact zone; hydrocarbons are separated, and the water is recycled to the top of the contact zone, resulting in a counter-current contact process. Also, while an operation has been described in which the pressure on the aqueous mixture separated from the residual gases is maintained substantially at the pressure of the fluid, the pressure on this mixture may be reduced to aid in the separation of the dissolved or absorbed hydrocarbons. Further, the hot fluid leaving separator 24 may be brought into heat exchange relationship with the aqueous medium leaving settler 38 to raise the temperature of the water and cool the fluid, rather than being used to heat the incoming well fluid as shown. In the operation described the pressure on the fluid at the time of mixture with the water is about well head pressure. As previously indicated, the pressure may be raised prior to contact with the water and this is considered especially desirable where the well head pressure is materially below 3,000 pounds per square inch. In cases of this type, usually no compression of the residual gases is necessary for returning them to the formation.

The present process may be applied to the treatment of a distillate fluid which is flowed from a distillate well at a temperature of about 140° F. and a pressure of about 2600 pounds per square inch. The fluid according to analysis has the following composition in terms of mol per cent of components: methane 89.46, ethane 3.13, propane 1.56, isobutane 0.74, n-butane 0.89, isopentane 0.37, n-pentane 0.48, and hexanes plus 3.37. The condensate recovered from this fluid will contain

the major portion of the hydrocarbons containing four or more carbon atoms.

Since changes may be made in the process described above without departing from the scope of the invention, it is intended that the description shall be interpreted as illustrative and not in a limiting sense.

I claim:

1. The process of recovering heavier, liquefiable hydrocarbons from a hydrocarbon mixture flowed at a high temperature and pressure from a well tapping a distillate reservoir, which comprises passing hydrocarbons of said mixture under high temperature and pressure conditions within the critical region for said hydrocarbons and such that the hydrocarbons are substantially entirely in a single homogeneous gas phase into intimate absorbing relationship with an essentially aqueous medium having solvent properties for the desired hydrocarbons under said high temperature and pressure conditions, to remove a substantial proportion of the heavier, liquefiable hydrocarbons and leave the greater part of the remainder of said hydrocarbons in said homogeneous gas phase.
2. The process of recovering heavier, liquefiable hydrocarbons from a hydrocarbon mixture flowed at a high temperature and pressure from a well tapping a distillate reservoir, which comprises passing hydrocarbons of said mixture under high temperature and pressure conditions within the critical region for said hydrocarbons, the temperature being above 200° F. and the temperature and pressure together being such that the hydrocarbons are substantially entirely in a single homogeneous gas phase, into intimate absorbing relationship with an essentially aqueous medium having solvent properties for the desired hydrocarbons under said high temperature and pressure conditions, to remove a substantial proportion of the heavier, liquefiable hydrocarbons and leave the greater part of the remainder of said hydrocarbons in said homogeneous gas phase.
3. The process in accordance with claim 2 in which the temperature at which the hydrocarbons of said mixture are passed into intimate absorbing relationship with the essentially aqueous medium is within the range of 400 to 600° F.
4. The process of recovering heavier, liquefiable hydrocarbons from a hydrocarbon mixture flowed at a high temperature and a pressure above 1500 pounds per square inch from a well tapping a distillate reservoir, which comprises passing hydrocarbons of said mixture under high temperature and pressure conditions within the critical region for said hydrocarbons, said temperature being above 200° F. and said pressure above 1500 pounds per square inch, said temperature and pressure together being such that the hydrocarbons are substantially entirely in a single homogeneous gas phase, into intimate absorbing relationship with an essentially aqueous medium having solvent properties for the desired hydrocarbons under said high temperature and pressure conditions, to remove a substantial proportion of the heavier, liquefiable hydrocarbons and leave the greater part of the remainder of said hydrocarbons in said homogeneous gas phase.
5. The process in accordance with claim 4 in which the temperature at which the hydrocarbons of said mixture are passed into intimate absorbing relationship with the essentially aqueous medium is within the range of 400 to 600° F.
6. The process of recovering heavier, liquefiable hydrocarbons from a hydrocarbon mixture flowed

at a high temperature and a pressure above 1500 pounds per square inch from a well tapping a distillate reservoir, which comprises passing hydrocarbons of said mixture under high temperature and pressure conditions within the critical region for said hydrocarbons, said temperature being above 200° F. and said pressure being above 1500 pounds per square inch, said temperature and pressure together being such that the hydrocarbons are substantially entirely in a single homogeneous gas phase, into intimate absorbing relationship with an aqueous medium comprising a hydroxy-organic compound soluble in water at said high temperature, said aqueous medium having solvent properties for the heavier, liquefiable hydrocarbons under said high temperature and pressure conditions, to remove a substantial proportion of the heavier, liquefiable hydrocarbons and leave the greater part of the remainder of said hydrocarbons in said homogeneous gas phase.

7. The process of recovering heavier, liquefiable hydrocarbons from a hydrocarbon mixture flowed

at a high temperature and a pressure above 1500 pounds per square inch from a well tapping a distillate reservoir, which comprises passing hydrocarbons of said mixture under high temperature and pressure conditions within the critical region for said hydrocarbons, said temperature being above 200° F. and said pressure being above 1500 pounds per square inch, said temperature and pressure together being such that the hydrocarbons are substantially entirely in a single homogeneous gas phase, into intimate absorbing relationship with an aqueous medium comprising an agent for reducing the surface tension of water, said aqueous medium having solvent properties for the heavier, liquefiable hydrocarbons under said high temperature and pressure conditions, to remove a substantial proportion of the heavier, liquefiable hydrocarbons and leave the greater part of the remainder of said hydrocarbons in said homogeneous gas phase.
